2,462,963

DERIVATIVES OF p-AMINOBENZENESULFONAMIDES AND PROCESS OF MAKING SAME

Max Hartmann and Jean Druey, Bielen, Switzerland, assignors to Ciba Pharmaceutical Products Inc., Summit, N. J., a corporation of New Jersey

No Drawing. Application July 30, 1943, Serial No. 496,838. In Switzerland April 14, 1943

2 Claims. (Cl. 260—238.6)

1

The suggestion has already been made that chemotherapeutically active p-aminobenzenesulphonamides which are only slightly soluble in water should be made water-soluble by the introduction into the amino group of a radical containing a salt-forming group. The previous processes of this kind had the disadvantage of being difficult to carry out, or of giving compounds which are considerably less active on parenteral administration than the unsubstituted amines. These water-soluble derivatives are presumably not decomposed rapidly enough, with the result that the parent amines are not able to exert their full effect.

It has now been found that derivatives of 15 p-aminobenzenesulphonamides which are water-soluble and at the same time parenterally active can be obtained in a satisfactory way if chemotherapeutically active p-aminobenzenesulphonamides which are substituted in the sulphonamide group by a polyheteroatomic, heterocyclic radical are caused to react with salts of glyoxylic acid, with this free acid or with compounds convertible into glyoxylic acid or into its salts and, if necessary, converting the compounds obtained into water-soluble salts of the corresponding carboxylic acids.

Amongst the p-aminobenzenesulphonamides mentioned as parent products, 2-(p-aminobenzenesulphonamido)-thiazole is particularly suitable. Other compounds, which are substituted in the sulphonamide group by a polyheteroatomic, heterocyclic radical containing sulphur in the ring, can also be used e. g. 2-(p-aminobenzenesulphonamido)-4,5-dihydrothiazole or 2-(p-aminobenzenesulphonamido)-thiodiazoles such as 2-(p-aminobenzenesulphonamido)-5-ethyl-thiodiazole. It is also possible to start from p-aminobenzenesulphonamido-pyrimidines e. g. 6-(p-aminobenzenesulphonamido)-2,4-dimethyl-pyrimidine or from p-aminobenzenesulphonamido-pyrazines.

Particularly suitable salts of glyoxylic acid are the alkali salts, but the alkaline earth or ammonium salts or the salts with organic bases can also be used for the reaction. As compounds convertible into glyoxylic acid or its salts may be mentioned, for example, glyoxylic acid esters, glyoxylic acid ester hemiacetals, thioglyoxylic acid, diacetoxy-acetic acid, dihalo-acetic acids, etc.

The reaction should be advantageously carried out in such a way that the p-aminobenzenesulphonamides, in particular the 2-(p-aminobenzenesulphonamido)-thiazole, are caused to re-

act with glyoxylic acid salts, for example with sodium glyoxylate in water, if necessary adding a solvent which is miscible with water, e. g. alcohol. The reaction can also be carried out in the presence of organic solvents, particularly if glyoxylic acid or its esters are used. The compounds obtained in the form of the free carboxylic acids, esters, etc. can be converted in a known manner into any water-soluble salt e. g. the sodium, ammonium or calcium salt.

The constitution of the new compounds can not be exactly determined. The analytical results give the following probable formulae:

wherein R represents a polyheteroatomic, heterocyclic radical. The salts may contain, in addition, crystal solvents.

The compounds obtained by the present process dissolve readily in water in the form of their salts. The neutral solutions which can be prepared from the salts are therefore particularly suitable for parenteral administration and have the same activity as the parent p-aminobenzenesulphonamides, the latter being presumably reformed in the body.

The appended claims are directed to the preferred form of the invention, involving the reaction between sodium glyoxylate and 2-(p-aminobenzenesulphonamido)-thiazole, and the resulting product.

Example 1

40 12.5 gm. of sodium glyoxylate are dissolved in 80 ccm. of water and the solution heated to about 80° C. 25 gm. of 2-(p-aminobenzenesulphonamido)-thiazole are then introduced, stirring continually, and are dissolved completely within a 45 short time. Any impurities can be filtered off. The solution is poured into alcohol, stirring continually, when the condensation product separates out in the form of a white powder. It is filtered off by suction, washed with alcohol and ether and dried at 100° C.

The corresponding calcium salt can be obtained from this compound by reaction with calcium chloride; it is less soluble in cold water than the sodium compound, but fairly soluble 55 in warm water.

Example 2

11 gm. of 75 per cent glyoxylic acid are dissolved in 80 ccm. of water and neutralized with sodium bicarbonate. To the warm solution, 28 gm. of 2-(p-aminobenzenesulphonamido)-5-ethyl-thiodiazole are introduced, dissolving quickly. The condensation product is precipitated with alcohol from the still warm solution. It is a white, water-soluble powder. The solubility is somewhat less than of the compound described in Example 1.

The glyoxylic acid may be neutralized with an organic base e. g. amino-ethanol.

Example 3

7.2 gm. of 2-(p-aminobenzenesulphonamido)-thiazole are added to 60 ccm. of hot absolute alcohol containing 6.2 gm. of 68 per cent glyoxylic acid, a clear solution being obtained after a short time. After cooling, the condensation product is precipitated with ether, filtered off by suction and dried. It is a somewhat yellowish powder which dissolves easily in sodium bicarbonate. The new compound does not have any real melting point. On heating it turns dark above 170° C. and decomposition starts at 210-220° C., with frothing.

In the same way a condensation product, which dissolves readily in bicarbonate to give a clear solution, can be obtained from 6-(p-aminobenzenesulphonamido)-2,4-dimethylpyrimidine and glyoxylic acid.

Example 4

25 gm. of 2-(p-aminobenzenesulphonamido)-thiazole are dissolved in 250 ccm. of hot glacial acetic acid and a warm solution of 15 gm. of glyoxylic acid ethyl-ester hemi-acetal in 150 ccm. of glacial acetic acid added. On cooling, a yellowish sticky substance soon begins to separate out, rapidly becoming solid on further cooling. The yield is about 28 gm. The new compound does not melt below 300° C.; above 150° C. it gets darker and darker.

To saponify the ester group, 6 gm. of the substance are dissolved in 30 ccm. of 2N NaOH and

allowed to stand for 20 hours at 20° C. The solution is then neutralized by the addition of 20 ccm. of 2N HCl and separated from the precipitated amorphous substances. On precipitation with alcohol, a compound is obtained, whose properties agree with those of the sodium salt described in Example 1.

What we claim is:

- 10 1. A process for the manufacture of a derivative of a para-aminobenzenesulphonamide, comprising treating 2-(para-aminobenzenesulphonamido)-thiazole with sodium glyoxylate in a solvent medium whereby the para-amino group of the 2-(para-aminobenzenesulphonamido)-thiazole reacts with the aldehyde group of the sodium glyoxylate.
- 20 2. The compound obtained by a process consisting in treating 2-(para-aminobenzenesulphonamido)-thiazole with sodium glyoxylate in a solvent medium whereby the para-amino group of the 2-(para-aminobenzenesulphonamido)-thiazole reacts with the aldehyde group of the sodium glyoxylate.
